UNITED STATES PATENT OFFICE.

MORRIS L. ORUM, OF PHILADELPHIA, PENNSYLVANIA.

MORTISE-LOCK.

SPECIFICATION forming part of Letters Patent No. 367,436, dated August 2, 1887.

Application filed February 26, 1887. Serial No. 228,978. (No model.)

To all whom it may concern:

Be it known that I, MORRIS L. ORUM, of Philadelphia, in the county of Philadelphia and State of Pennsylvania, have invented certain new and useful Improvements in Mortise-Locks; and I do hereby declare the following to be a full, clear, and exact description of the invention, such as will enable others skilled in the art to which it appertains to make and use to the same.

My invention relates to an improvement in mortise locks the object being to construct a machine lock, used for cabinet or other purposes, so that a secure means of attachment of the lock to the mortise is afforded in an economical and simple manner, a superior lock being produced at a low initial cost.

With these ends in view my invention consists in certain features of construction and combination of parts, that will be hereinafter explained, and pointed out in the claims.

Referring to the drawings, Figure 1 is a plan view of the face-plate of my improved lock. Fig. 2 is a plan view of another form of face-plate with my improvement combined therewith. Fig. 3 is a side elevation of the face-plate of the lock. Fig. 4 is an elevation in cross-section of the face-plate, showing its position in a mortise.

In locks used for cabinet or other similar work it is desirable to afford a means of securing the lock-body in the open recess or mortise made to contain it without the use of retaining-screws. Locks have been made to accomplish this desideratum, but in a comparatively expensive manner. In order to effect the retention of the lock-body simply and reliably, I have devised a method of construction that avoids multiplication of parts and consequent expensive hand-work to join such pieces.

My improvement is embodied in a novel face-plate of the lock, which, by its peculiar form, holds the attached cap and contained mechanism firmly in place in a proper cavity made for it.

One form of the face-plate is shown at A, Figs. 1 and 3. This is preferably struck by dies from sheet metal, and is provided with the usual selvage, B, at one end and is rounded

at the opposite end, B'. The parallel edges C of the face-plate A are furnished with wings D D, cut therefrom and bent inwardly at an acute angle to the flat surface of the face-plate. Any suitable number of these inclined integral wings D may be formed on the edges of the face-plate A, and also on its rounded end. The cutting and bending inwardly of the wings D will permit a corresponding number of flanges, E E, to remain and extend in the same plane as the general surface of the face-plate A.

The cap-plate is attached to the face-plate A in any approved manner, and is placed inside the interior boundaries of the inclined wings D. The interior or locking mechanism may be of any approved form of construction adapted to this style of lock, as my present improvement does not extend to such parts of the lock, and can be applied to any cabinet-lock.

In Fig. 2 a rectangular face-plate, G, is shown. This is furnished with the inclined wings D D, which are identical in form with those shown on plate A, and the flanges E are left integral with the body of the plate, as shown.

In operation the mortise made in the door, drawer, &c., to receive the body of the lock is cut with overhanging edges that conform to the angle of and form bearing for the outer surfaces of the wings D D of the face-plate A or G, while the flanges E rest snugly against the outer face of the door or drawer. The plate is forced into place by a sliding movement, the wings D and flanges E embracing and interlocking in such a manner with the edges or walls of the mortise as to prevent any lateral displacement of the face-plate, and also prevent the removal of the latter in any direction except the reverse of that in which it was inserted in the mortise. The degree of elasticity that is afforded the wings D by their method of construction will permit them to yield slightly and spring outwardly to hold the lock in position in the cavity made for it.

It will be seen that the locking contact of parts just described will cause a compression of the walls of wood that form the sides of the routed cavity made for the lock and a clamping of these wood portions between the slightly elastic flanges E and the exterior surface of

the inclined wings D, so that the depth of the cavity is not depended upon to retain the body of the lock in rigid position.

The wing formed on the edge of the face-plate opposite the selvage is designed to engage the lower edge or wall of the cavity or mortise just as the selvage comes flush with the outer edge of the door or drawer and holds the plate against displacement.

Having fully described my invention, what I claim as new, and desire to secure by Letters Patent, is—

1. In a mortise or cabinet lock, a face-plate having a selvage on one end and alternating series of flanges and inclined wings on its opposite side edges, the said wings being ar-

ranged at acute angles to the face-plate, substantially as set forth.

2. In a mortise or cabinet lock, a face-plate having wings arranged at acute angles to the inner face of the face-plate and straight projecting flanges, the said wings and flanges formed integrally with the plate on all its edges except the selvage edge, substantially as set forth.

In testimony whereof I have signed this specification in the presence of two subscribing witnesses.

25 MORRIS L. ORUM.
